HEAT EXCHANGE SYSTEM CONTROL

Lyman F. Whitney, Boston, Mass., assignor to
 Comstock & Wescott, Inc., Boston, Mass., a
 corporation of Massachusetts

Application January 30, 1931. Serial No. 512,405

11 Claims. (Cl. 122—504)

This invention relates to a control arrangement for boilers and/or heat exchange systems such as refrigerating systems and in one aspect relates to means arranged to impede or stop the heating of a boiler when an insufficient amount of liquid is supplied to the same or the liquid in the boiler is depleted for any reason.

This invention affords a safety arrangement for a refrigerating system which employs a boiler and which may include means for maintaining a low subatmospheric pressure in the system. In accordance with the present invention, the system may be so arranged that an increase in the internal pressure thereof, due, for example, to the leakage of air into the system or to the failure of the purger to operate will be effective in causing the depletion of the liquid in the boiler and consequent interruption to the supply of heat to the boiler, while the heating of the boiler will also be interrupted should the liquid level therein become unduly low for any other reason.

The present invention provides an arrangement which is particularly adapted to employment in systems having a pipe or duct connected to the boiler and normally containing liquid as, for example, liquid that is being fed to the boiler. Thus the invention may be employed in refrigerating systems having vaporizers or boilers, the liquid in which is being replenished by means of a duct which may contain a column of the fluid to be vaporized. For example, this invention is particularly advantageous when employed with a refrigerating system of the character disclosed in the Patent No. 1,761,551 to Eastman A. Weaver dated June 3, 1930 and the copending application of Daniel F. Comstock, No. 198,715, filed June 14, 1927 as well as my copending application, Serial No. 503,006 filed December 17, 1930. The above identified patent and applications disclose refrigerating apparatus which includes a boiler or vaporizer for the propellant fluid, which preferably may be mercury, and the vapor of which is supplied to the aspirator nozzle for entrainment of refrigerant vapor from a cooler, the propellant being condensed after the entrainment of the refrigerant and returned through a pressure balancing column to the boiler.

In accordance with the present invention, a suitable control factor may be provided to interrupt the application of heat to the boiler when the liquid level in the latter becomes inordinately low. Such a control factor preferably is associated with the duct which feeds liquid to the boiler, and it may include a thermostatic element which is actuated when the liquid contained

within the duct is displaced by the vapor, which ordinarily has a much higher temperature than the liquid in this part of the system, and has a much greater heat supplying power.

Thus, in the case of a boiler provided with a gas burner, a thermostatic control member may normally serve to retain a valve in the fuel supply line in its open position, while an increase in the temperature of the thermostatic member may be effective in causing the valve to close, thus interrupting the flow of fuel to the burner.

A further aspect of the invention relates to the arrangement of a low pressure system such as a refrigerating system which is provided with means that interrupt the normal flow of liquid to the boiler should the pressure within the system rise due to the leakage of atmospheric air or for any other reason. The system is arranged so that such an increase in pressure will result in lowering of the liquid level in the boiler, whereupon the control device operates to interrupt the supply of heat to the boiler and thus stop future operation of the system.

In the accompanying drawings:

Fig. 1 is a schematic view of a refrigerating system to which my safety control arrangement is applied;

Fig. 2 is an enlarged horizontal section through the control member and the associated liquid duct;

Fig. 3 is a section indicated by line 3—3 of Fig. 2;

Fig. 4 is a top view of the control means, showing the fluid pipe in section; and

Fig. 5 is an elevational view of the thermostatic element.

Fig. 1 illustrates typical apparatus to which my control system may be applied, such as a refrigerating system employing a heavy propellant of comparatively high boiling point, for example mercury, and a lighter, more volatile refrigerant such as water; this system being of the same general character as disclosed in the above-identified patent of Eastman A. Weaver.

This system may be provided with a boiler 1 having a central firebox 2 into one end of which a burner 3 projects. A suitable flue 4 may be provided to permit exhaustion of gases from the firebox, and a fuel supply duct 6 may be connected to the burner 3, being arranged to receive fuel from any suitable source such as the city gas mains.

A vapor duct 7 extends upwardly from the boiler 1 to an aspirator nozzle 8 which projects into an entraining chamber 9. A vapor duct 10

connects chamber 9 with the upper part of a cooler 12 which contains a liquid body of refrigerant such as water. Propellant vapor passing from the nozzle 8 at high speed is effective in entraining vapor from the cooler 12 and in causing rapid evaporation at the surface of the contained liquid thereby causing the cooler to have a low temperature. The mixture of propellant and refrigerant vapors passes into the compression and condensing funnel 15 which is aligned with the aspirator nozzle and which is provided with suitable cooling means such as fins 16, so that the high boiling point propellant may be condensed out of the vapor mixture. The funnel 15 is inclined and propellant condensed therein flows downwardly to a downwardly extending propellant drain 17.

An upwardly extending vapor duct 19 is joined to the intermediate part of a separating chamber 20, the upper portion of which is connected to a refrigerant condenser 21. The vapor received by the condenser 21 is liquefied and flows back to the chamber 20, passing out of the lower part of the same into the duct 22 which forms one leg of a trap 23 that may contain mercury. The opposite leg of this trap is connected by a duct 25 with the cooler 12. The condensed refrigerant forms a liquid column in duct 22, which reaches a sufficient height to balance the mercury column in the opposite leg of the trap 23, so that the refrigerant from the bottom of the column passes through the trap into duct 25 and thus returns to the cooler 12.

Preferably a system of this character may operate at subatmospheric pressure, and may be provided with means to interrupt the return of propellant to the boiler when the internal pressure of the system rises unduly, as for example, due to leakage of atmospheric air into the system. The system preferably may be provided with a purger or evacuating means automatically operable to exhaust gases from the system to aid in maintaining a low internal pressure and to compensate for any slight leakage that may occur. For this purpose a duct 30 is connected to the upper part of the condenser 21 and is arranged to receive non-condensable gases. The propellant from the drain 17 flows through a trap 31 that is connected to an entraining chamber 33, the upper part of which communicates with the duct 30. A downwardly extending tube 34 of restricted diameter is connected to the lower part of chamber 32 and is so dimensioned that globules of the propellant will pass downwardly through the same, acting as separate liquid pistons between which bodies of non-condensable gas may be entrained. The lower end of tube 34 is connected to a receptacle or standpipe 35 having an enlarged upper portion or reservoir 36 which is open to the air. A propellant receiving duct 39 is connected to the lower part of the standpipe and extends upwardly to the downwardly inclined duct 40, the juncture of ducts 39 and 40 providing a spill-over which determines the pressure at the lower end of the tube 34 and the standpipe 35. The duct 40 is joined to a main propellant return pipe 32, the lower end of which is connected to the lower part of boiler 1. The return pipe 32 is provided with an upwardly extending continuation 29 that forms a drain to receive propellant particles which may condense in the mixing chamber 9.

A mercury containing trap 27 may be connected to the bottom of the cooler 12 to receive stray propellant particles therefrom, this trap

being connected to a pipe 28 which is joined to the duct 40. Accordingly as additional mercury is received by the trap 27 from the cooler, some of the mercury will pass from the trap through duct 28 and thus be returned to the propellant circuit.

It is thus evident that in the operation of a system of this character mercury is vaporized in the boiler 1, passing to the aspirator nozzle 8 and mixing chamber 9, and entrains refrigerant vapor from the cooler 12, the mercury being condensed out of the mixture in the funnel or condenser section 15 and the refrigerant vapor passing upwardly to the refrigerant condenser 21; the condensed refrigerant from the latter passes through the pressure balancing trap 23 and thus returns to the cooler 12.

The major portion of the condensed propellant is received by the drain 17 and thus passes through trap 31 to the chamber 32 and the tube 34. Non-condensable gases which occur in the system are received from the pipe 30 and entrained between propellant globules that pass downwardly through tube 34. The standpipe 35 normally contains a column of mercury which has its upper surface exposed to atmospheric pressure; accordingly, the non-condensable gases bubble upwardly through this mercury column and are exhausted to the atmosphere. The mercury from tube 34 and standpipe 35 will rise through duct 39 and spill over into duct 40, thus being received by the propellant return duct 32 which contains a pressure balancing column of mercury. The mercury passes from the lower end of this column to the boiler 1. Should the amount of non-condensable gases received by the purger be less than its normal pumping capacity, refrigerant vapor may be entrained in the pipe 34 and rise to the top of the mercury column in standpipe 35, thus being emitted from the system. However, the amount of vapor which is thus exhausted even over a long period of time is substantially negligible. Should the pressure within the system rise due to the leakage of gases or atmospheric air into the system at a greater rate than it may be exhausted by the purger, the internal pressure will cause the mercury level in standpipe 35 to rise against atmospheric pressure so that the mercury may flow upwardly into the reservoir 36. The capacity of this part of the system is so determined that an increase in the internal pressure of the system to a predetermined point will result in the collection of so much mercury in the standpipe and the reservoir that continued flow of mercury upwardly through duct 39 to duct 40 will be interrupted and the supply of propellant in the boiler will quickly become depleted so that vapor may pass upwardly into duct 32.

It will be understood that a system of the character just disclosed has been described as representing a typical arrangement to which my safety control means is particularly applicable, but that this control means may be applied to many other types of systems, for example, to a system such as shown in my copending application Serial No. 503,006 which is provided with a propellant lifter to permit the top of the pressure balancing column of mercury which returns propellant to the boiler to be at a level above the propellant condenser.

In accordance with the present invention, control means may be associated with a duct which contains liquid and is connected to the vaporizer below the normal liquid level therein, the control

means being arranged to be responsive to an elevation in the temperature of the fluid within the duct, so that whenever the fluid is displaced by vapor due to an abnormal lowering of the liquid level in the boiler, the supply of heat to the boiler is interrupted. For this purpose, the control means is arranged to interrupt the supply of heat to the boiler in whatever manner that supply may be effected; thus with a boiler having a burner for a combustible mixture, such as a mixture of illuminating gas and air, the control means may include a valve to interrupt the flow of at least one of the ingredients of combustion to the burner. This control means includes a part to interrupt the flow of fuel or energy to the heating factor 3 of the boiler and accordingly may be associated with the fuel supply duct 6. As shown in Fig. 2, the latter may be connected to a casing 50 which is disposed in heat transfer relation to the duct 32, and preferably is located adjoining flue 4. Figs. 2, 3 and 4 illustrate this arrangement in greater detail, it being evident that the casing 50 is provided with an outlet portion or connection 51 which is joined to the section of duct 6 that extends to the burner and also is provided with the inlet connection 52 that is connected to the section of duct 6 that is connected to the gas mains or other source of fuel supply.

The casing 50 is provided with a substantially cylindrical recess which has an open end opposite the connection 51 and which is provided with internal threads 54 to receive external threads upon a cylindrical member 55. The latter may be provided with an external head 56 to facilitate its movement into and out of threaded engagement with the casing and to provide a shoulder for engagement with an annular face of the casing.

Member 56 is provided with a cylinder internal recess 57 which receives a slidable valve member 58, the latter having a substantially cylindrical body portion 59 with a central recess 60 that receives a compression spring 61. The latter has one end normally in engagement with valve 58 and its opposite end in engagement with the head 56 of member 55 so that it tends to urge the valve toward the connection 51.

The mouth of a passage 65 which extends to connection 51 is provided with a beveled surface 66 to form a valve seat that cooperates with a tapered extension 69 upon the end of member 58. Thus when the spring 61 is free to operate, the member 69 engages the valve seat 66 and flow of fuel from the inlet 52 through the casing 50 to the outlet 51 is prevented.

During normal operation of the system, however, I prefer to provide means locking the valve in open position. Such means comprises a segmental member 70 of thermostatic metal which is illustrated more particularly in Figs. 3 and 5, this thermostatic member having an end portion secured by a fastening element 71 in a groove 72 in the cylindrical member 55. The body portion 59 of the valve member may be cut away to clear the end of element 71 (Fig. 3). A continuation of the groove 72 provides a slot 73 which permits the thermostatic member to engage a segmental groove 74 in valve 58, thereby locking the latter in its open position and holding the spring 61 under compression. The member 70 is arranged, however, so that in response to a suitable increase in its temperature, it will spring out of engagement with the groove 74, thus releasing the valve member 58, so that the spring

is effective in engaging valve surface 69 with the seat 66, thereby interrupting the fuel flow.

A plate 80 having a semi-cylindrical recess is secured by screws 82 to a portion of the casing 50 which has a complementarily formed recess, 80 these recesses cooperating to provide a substantially cylindrical opening through which the duct 32 extends, the plate and screws being effective in clamping the duct in good heat transfer relation to casing 50.

During normal operation of the system the duct portion 32 adjoining casing 50 contains liquid propellant and the valve will be held in its open position. When the liquid in the boiler 1 is depleted for any reason, as, for example, due to the clogging of the aspirator nozzle 8, the vapor will displace the liquid mercury in the lower part of the duct 32 and vapor will pass to the region of the casing 50. Obviously this propellant vapor has a temperature which is distinctly higher than that of the liquid normally contained in the duct 32, and can rapidly conduct heat to the casing 50 so that the thermostatic element 70 expands and moves out of engagement with the groove 74 in the valve member 58, permitting the latter to be moved to its closed position by spring 61. It is evident that in case of an undue increase in the internal pressure of the system, for example due to rapid leakage of atmospheric air into the system, the mercury will rise into the reservoir 36 and will no longer be supplied to the duct 32 through the duct 40. The downwardly flowing propellant received by duct 32 from duct 40 normally aids the cooling of the pipe 32 and casing 50, thus tending to offset the heating effect of the juxtaposed flue, but as soon as this flow is interrupted, for example, due to the collection of propellant in receptacle 36 the heat from the flue is effective in causing a rapid increase in the temperature 115 of the casing 50 and the heat-responsive element 70. Thus the heat from flue 4 not only causes the more rapid operation of the shut-off device, in response to abnormal operating conditions; but under certain conditions, this heat may be 120 effective in causing operation of the device, before the liquid propellant passes out of the lower end of duct 32. Accordingly further supply of fuel to the boiler is prevented and the operation 125 of the system is interrupted.

In order to permit the system to resume operation, it is necessary to remove the members 55 and 58 from the casing 50, reassembling them in their normal position with the spring 61 compressed so that the cooled and contracted thermostatic element 70 may again engage the groove 74. This arrangement is effective in calling attention to the condition which has caused the development of the high pressure in the vaporizer and an indication is thus afforded of the advisability of expert attention to the system.

From the foregoing, it will be evident that I have provided safety control means to interrupt the supply of heat to the boiler which is connected to a duct that normally contains liquid, but which will contain vapor whenever the boiler pressure becomes inordinately high or whenever the liquid level becomes undesirably low in the boiler. Accordingly, this arrangement is effective in interrupting the operation of the system when the flow of propellant to the boiler is interrupted or unduly impeded as for example due to the leakage of atmospheric air into the system and the collection of mercury in reservoir 36. Furthermore, should the aspirator nozzle 8 become 150

clogged the pressure in the boiler will become sufficiently high to displace the mercury and to cause vapor to flow upwardly into the duct 32 thus causing operation of the shut-off means. 5 If a leak should develop in the boiler so that the level of the mercury should become unduly low, a similar result will take place. An arrangement of this character is particularly advantageous with a system having a propellant lifter such as 10 that disclosed in my copending application, Serial No. 503,006 which is included by reference herein. Should such a propellant lifter fail to operate for any reason and thus terminate the return of propellant to the boiler, the shut-off means will 15 operate in the same manner to protect the system against injury and to prevent burning of the boiler. It is thus evident that I have provided means to interrupt operation of the system under practically any condition which would 20 make continued operation dangerous or undesirable.

It should be understood that the present disclosure is for the purpose of illustration only and that this invention includes all modifications and 25 equivalents which fall within the scope of the appended claims.

I claim:

1. Apparatus of the class described comprising 30 a boiler, a burner associated therewith, a passage supplying fluid to the burner, a vapor outlet pipe connected to the boiler, a duct normally containing liquid connected to the boiler, a heat distortable thermostat in heat transfer relation to a portion of the duct remote from the boiler, said duct being arranged so that depletion of liquid in the boiler will cause hot vapor to pass into the duct and effect movement of the thermostat, a shut-off valve in the fluid passage, a spring urging the valve toward its closed position, the thermostat normally locking the valve in open position and when actuated by heat releasing the valve so that it is closed by the spring, thus interrupting the flow of fluid to the burner.

2. Apparatus of the class described, comprising 45 a boiler, a burner associated therewith, a fuel supply pipe leading to the boiler, a liquid supply duct connected to the boiler and normally containing a column of liquid to balance boiler pressure and to supply liquid to the boiler, a valve casing in heat transfer relation to a portion of said duct and connected to the pipe, a movable valve member in said casing arranged when in engagement with a seat in the casing to interrupt fuel flow through the pipe, a spring in 50 the casing urging the valve toward the seat, a thermostat normally engaging a recess in the valve member to hold it away from the seat, said thermostat being movable out of said recess to release the valve in response to a high temperature.

3. Apparatus of the class described comprising 65 a boiler, a vapor outlet pipe connected to the upper part of the boiler, an aspirator nozzle connected to said pipe, a duct connected to the lower part of the boiler and normally containing a displaceable liquid column, said duct having an upper portion disposed above the boiler and normally free from liquid, means for supplying heat to the boiler, a shut-off to terminate the supply of heat to the boiler, a thermostat operable under the influence of heat to cause the shut-off to interrupt the supply of heat, said thermostat being disposed adjoining the duct, 70 whereby clogging of the nozzle and consequent high vapor pressure in the boiler causes vapor

from the boiler to displace the liquid column in the duct, so that the thermostat will cause the shut-off to operate.

4. Apparatus of the class described comprising 80 a fluid circuit including a boiler, a vapor outlet pipe connected to the upper part of the boiler, a supply duct connected to the lower part of the boiler and normally containing a displaceable liquid column, means for supplying heat to the boiler, a shut-off to terminate the supply of heat, 85 a heat-responsive element operable under the influence of heat to cause the shut-off to interrupt the supply of heat, said heat-responsive element being disposed adjoining the supply duct, and means operable in response to a pressure change in the circuit to interrupt flow of liquid into the supply duct and thence to the boiler, whereby vapor will flow to the region of the thermostat and cause operation of the shut-off.

5. Apparatus of the class described comprising 90 a fluid circuit having a low pressure portion normally operating at subatmospheric pressure and including a boiler, a vapor outlet pipe connected to the upper part of the boiler, a supply duct connected to the lower part of the boiler and normally containing a displaceable liquid column, means for supplying heat to the boiler, a shut-off to terminate the supply of heat, a thermostat operable under the influence of heat to cause the shut-off to interrupt the supply of heat, said 100 thermostat being disposed adjoining the supply duct, and means operable in response to an increase in the pressure of said low pressure portion of the circuit to interrupt flow of liquid into the supply duct and thence to the boiler, whereby vapor will flow to the region of the thermostat and cause operation of the shut-off.

6. Apparatus of the class described comprising 105 a fluid circuit having a low pressure portion normally operating at subatmospheric pressure and including a boiler, a vapor outlet pipe connected to the upper part of the boiler, a supply duct connected to the lower part of the boiler and normally containing a displaceable liquid column, means for supplying heat to the boiler, a shut-off to terminate the supply of heat, a thermostat operable under the influence of heat to cause the shut-off to interrupt the supply of heat, said 110 thermostat being disposed adjoining the supply duct, and means operable in response to an increase in the pressure of said low pressure portion of the circuit to interrupt flow of liquid into the supply duct and thence to the boiler, whereby vapor will flow to the region of the thermostat and cause operation of the shut-off.

7. Apparatus of the class described comprising 115 a fluid circuit including a boiler, a heater associated therewith, a supply duct connected to the boiler, a vapor duct connected to the boiler, and a receptacle associated with the supply duct and communicating with the atmosphere, said receptacle containing a liquid column with its upper surface exposed to atmospheric pressure and arranged so that the height of said column may 120 vary in response to the ratio between internal pressure of the system and atmospheric pressure, the receptacle having a sufficient capacity to prevent further flow of liquid through the supply duct to the boiler when the pressure ratio reaches 125 a predetermined point, and control means operable to interrupt operation of the heater when 130

135 140 145 150

the flow of liquid to the boiler is thus interrupted. 8. Apparatus of the class described comprising a fluid circuit including a boiler, a heater associated therewith, a supply duct connected to the boiler, a vapor duct connected to the boiler, and a receptacle associated with the supply duct and communicating with the atmosphere, said receptacle containing a liquid column with its upper surface exposed to atmospheric pressure and arranged so that the height of said column may vary in response to the ratio between internal pressure of the system and atmospheric pressure, control means operable in response to the rise of liquid to a predetermined portion of the receptacle to stop operation of the heater.

9. Apparatus of the class described comprising a fluid circuit having a low pressure portion normally operating at subatmospheric pressure, means for causing fluid circulation in said circuit, and means associated with said first means to interrupt the circulation of fluid in response to an undue rise in the pressure of said low pressure portion of the circuit.

10. Apparatus of the class described comprising a fluid circuit having a low pressure portion

normally operating at subatmospheric pressure, means for causing fluid circulation in said circuit, purging means operable to exhaust non-condensable gases from the system, and means associated with said first means and the purging means to interrupt the circulation of fluid in response to an undue rise in the pressure of said low pressure portion of the circuit.

11. Apparatus of the class described, comprising a boiler, a combustion chamber associated therewith, a flue connected to said chamber, a vapor outlet duct connected to the upper part of the boiler, a liquid supply duct connected to the boiler below said outlet duct, a fuel line supplying a combustible fluid to the combustion chamber, shut-off means associated with said line and operable to impede the flow of fuel, a heat-responsive element normally restraining the shut-off device from operating, said element being in heat transfer relation to said flue and liquid supply duct, heat from the flue being effective in causing the heat-responsive element to release the shut-off means, thus impeding fuel flow, when the flow of liquid through the supply duct is interrupted.
